[57] **CLAIM**

The ornamental design for a single-bay electronics cabinet, as shown and described herein.

DESCRIPTION

FIG. 1 is a front view of the single-bay electronics cabinet according to the present invention;

FIG. 2 is a back view of the single-bay electronics cabinet of FIG. 1;

FIG. 3 is a right hand side view of the single-bay electronics cabinet of FIG. 1, the left hand side view being a mirror image;

FIG. 4 is a top view of the single-bay electronics cabinet of FIG. 1;

FIG. 5 is a bottom view of the single-bay electronics cabinet of FIG. 1;

FIG. 6 is a front and upper left perspective view of the single-bay electronics cabinet of FIG. 1; and,

FIG. 7 is a rear and upper right perspective view of the single-bay electronics cabinet of FIG. 1.
